US00D909958S

(12) **United States Design Patent** (10) Patent No.: **US D909,958 S**
Zhou et al. (45) Date of Patent: ** Feb. 9, 2021

(54) **BUSBAR-LESS SOLAR CELL**

(71) Applicant: **The Solaria Corporation**, Fremont, CA (US)

(72) Inventors: **Lisong Zhou**, Fremont, CA (US); **Huaming Zhou**, Wuxi Jiangsu (CN)

(73) Assignee: **THE SOLARIA CORPORATION**, Fremont, CA (US)

(**) Term: **15 Years**

(21) Appl. No.: **29/679,750**

(22) Filed: **Feb. 8, 2019**

Related U.S. Application Data

(60) Continuation of application No. 29/674,966, filed on Dec. 27, 2018, which is a division of application No. 29/624,308, filed on Oct. 31, 2017, now Pat. No. Des. 839,180.

Primary Examiner — Derrick E Holland

(57) **CLAIM**

The ornamental design for a busbar-less solar cell, as shown and described.

DESCRIPTION

FIG. 1 is a top perspective view of the first embodiment of a busbar-less solar cell showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a back elevation view thereof;

FIG. 7 is a front elevation view thereof;

FIG. 8 is a top perspective view of the second embodiment of a busbar-less solar cell showing our new design;

FIG. 9 is a top plan view thereof;

FIG. 10 is a bottom plan view thereof;

FIG. 11 is a right side elevation view thereof;

FIG. 12 is a left side elevation view thereof;

FIG. 13 is a back elevation view thereof; and,

FIG. 14 is a front elevation view thereof.

All elements shown in the top plan view of FIGS. 1, 2, 8 and 9 are structural lines on the surface and are flat with the top surface.

1 Claim, 6 Drawing Sheets
